[57] CLAIM

The ornamental design for an automatic thermostat control, as shown and described.

DESCRIPTION

FIG. 1 is a perspective view of an automatic thermostat showing my new design;

FIG. 2 is a front elevational view of the automatic thermostat control of FIG. 1;

FIG. 3 is a side elevational view of one side of the automatic thermostat control of FIG. 1;

FIG. 4 is a side elevational view of the other side of the automatic thermostat control of FIG. 1;

FIG. 5 is a rear elevational view of the automatic thermostat control of FIG. 1;

FIG. 6 is a top plan view of the automatic thermostat control of FIG. 1;

FIG. 7 is a bottom plan view of the automatic thermostat control of FIG. 1;

FIG. 8 is a front elevational view of the automatic thermostat control of FIG. 1, with the front door in the open condition;

FIG. 9 is a side elevational view of the automatic thermostat control of FIG. 1, with the front door in the open condition;

The broken line showing of the thermostat in FIG. 1 is for illustrative purposes only and forms no part of the claimed design.
